VENTILATING APPARATUS

Francis C. Kilb, Larchmont, N. Y., assignor to
 American Radiator Company, New York, N. Y.,
 a corporation of New Jersey

Application January 11, 1936, Serial No. 58,629

5 Claims. (Cl. 98—94)

My invention relates to ventilating apparatus, and more particularly to ventilating apparatus which is adapted to be arranged within the space defined by a partially raised window sash and a window sill.

My invention has for an object to provide an improved means for supporting and leveling ventilating apparatus of the window-mounted type.

10 The invention consists in the novel construction and combination of parts, to be more fully described hereinafter, and the novelty of which will be particularly pointed out and distinctly claimed.

15 In the accompanying drawings, to be taken as a part of this specification, I have fully and clearly illustrated a preferred embodiment of my invention, in which drawings—

Fig. 1 is a transverse vertical sectional view showing one preferred form of my improved window ventilator as mounted in a window opening, the section being taken on the line 1—1 of Fig 2;

Fig. 2 is a plan view of the structure shown in Fig. 1, the rear or outside of the ventilator being partially broken away to disclose the interior structure thereof; and

Fig. 3 is a fragmentary detail sectional view illustrating one preferred form of a supporting and leveling device carried by the outside or rear portion of the ventilator.

Referring now in detail to the construction illustrated, it will be observed that I have shown a ventilator 10 as arranged within an opening defined by a lower sash rail 11 of a window sash 12 and a window sill 13, the ventilator being supported by the sill 13. The window construction is of conventional form and comprises, in addition to the window sash and sill just described, vertically disposed jambs 14 in which the window 40 sash 12 slides. Filler blocks 15 are arranged at each side of the ventilator and serve to close the spaces between the ends of the ventilator and the window jambs.

A sealing member 16 extends longitudinally of the ventilator in the general plane of the window sash 12 and is secured to the ventilator by any suitable means such, for example, as spot welding. The member 16 comprises a horizontal flange 17, a vertical flange 18 and sealing material 19 secured to the flanges and engaged by the lower sash rail 11 of the sash 12. In the proper installed position of the ventilator 10, the vertical flange 18 is arranged parallel to and adjacent the inside lower face of the sash rail 11 (see Fig. 1).

55 The ventilator 10 comprises a casing 20 having

an inlet opening 21 in the rear part thereof and a pair of outlet openings 22 and 23 in the front and top parts, respectively. The inlet opening 21 is provided with fixed louvers 24 for preventing the entrance of water and snow into the ventilator. The outlet opening 22 is provided with adjustable louvers 25 for closing the opening or for directing the air to different desired portions of the room forwardly of the ventilator. The outlet opening 23 is provided with adjustable louvers 26 which serve either to close the opening or to direct the air from the ventilator upwardly from the ventilator, as desired.

Arranged within the ventilator is a longitudinally extending upright partition 27 dividing the 15 ventilator into an inlet chamber 28 communicating with inlet opening 21 and an outlet chamber 29 communicating with the outlet openings 22 and 23. Openings 30 are provided in the partition 27 and a motor blower unit 31 is arranged 20 within the inlet chamber 28 and operates to draw fresh air from the outside through the inlet opening 21 and chamber 28 and to force such air into the room through the openings 30, the outlet chamber 29 and the outlet openings 22 and 25 23. A longitudinally extending damper 32 is provided for preventing the flow of air through the ventilator when the motor blower unit is not operating. An operating rod 33 is connected to the damper 32 and extends exteriorly of the 30 ventilator where it may be grasped by the hand. In Fig. 1 the damper 32 is shown in full lines as being in its closed position and in dotted lines as being in its open position.

In accordance with the present invention, I 35 provide an improved means for supporting and leveling the ventilator in an opening defined by the partially raised window sash 12 and a window sill 13. The window sill 13 comprises an inside portion or stool 34 and an outside portion 40 or saddle 35, the latter being at a lower level than the inside portion 34 and sloping outward and downward to shed rain and snow. The ventilator 10 is supported at its front or inside portion by the inside sill portion 34, and is preferably positioned so that its center of gravity, indicated by the line A, is at the rear or outside of the inside sill portion 34.

The ventilator 10 is secured to the inside sill portion 34 by suitable angle brackets 38 carried 50 by the ends of the ventilator and screws 39 threaded into the sill portion 34. A strip of felt or other sealing material 40 is arranged longitudinally of the ventilator and between the bottom thereof and the inside sill portion 34. The 55

rear or outside portion of the ventilator overhangs the sill portion 35 and its unsupported weight is carried by jack screws 42 held by a nut device 43 fixed to the inside rear of the ventilator. 5 There are two jack screws 42 shown, one being at each end of the ventilator.

In addition to the function of carrying the unsupported weight of the ventilator, the jack screws 42 may be adjusted vertically to level the 10 ventilator and to properly position the flange 18 and the sash rail 11.

From examination of Fig. 3, it will be observed 15 that the nut device 43 comprises a pair of parallel spaced members 50 and 51 joined together at one side by a third member 52. The member 50 is fixedly secured to the inside and bottom of the ventilator 10 by any suitable means such, for example, as spot welding. The members 50 and 51 are provided with aligned screw threaded 20 openings 53 and 54, respectively, which are arranged in horizontal planes and receive the jack screw 42. The members 50 and 51 are also provided with aligned openings 55 and 56, respectively, the opening 55 being screw threaded. A 25 locking screw 57 loosely fits the opening 56 and threadedly engages at its lower end the opening 55 in the member 50.

The operation of the jack screw 42 will be apparent from the above description. When the 30 jack screw has been adjusted so that the ventilator is properly leveled and supported at the rear by the outside sill portion and the flange 18 at the inside rear face of the rail 11, the locking screw 57 may be turned until the head thereof 35 engages and moves the outside part of the member 51 relatively to the member 50 and jams the mating threads of the jack screw and the openings 53 and 54, thereby preventing further turning of the jack screw.

40 From the above description, it will be apparent that I have provided a very simple, inexpensive and effective method of supporting and leveling window ventilators in window openings. The ventilator cannot be moved forward or backward 45 on the window sill due to the brackets 38 and screws 39. The weight of the ventilator is carried by the inside window sill 34 and by the outside sill 35 through the jack screws 42. The jack screws are readily accessible by raising the window sash 12 and then raising the rear portion 59 50 of the top of the ventilator which is suitably hinged at 60 and carries at its forward longitudinal edge the sealing member 16.

What I claim and desire to secure by Letters 55 Patent of the United States is:—

1. The combination with a window comprising 60 upright jambs, a window sash slidably mounted in the jambs and a window sill including an inside sill portion and an outside sill portion at a lower level than said inside sill portion; of a ventilator comprising a casing structure adapted to be arranged within the window opening with a front part supported by the inside sill portion and a rear part overhanging said outside sill portion; said casing including a cover member hinged along one side so that it may be readily opened and access may be had to the rear interior thereof; and adjustable supporting and leveling means arranged within the rear of the ventilator and 65 accessible only from the interior thereof when the cover is opened, and including an adjustable part extending downwardly through the bottom of the casing and engaging the outside sill portion for supporting the rear part of the ventilator from the outside sill portion. 70

2. The combination with a window comprising 75 upright jambs, a window sash slidably mounted in the jambs and a window sill including an inside sill portion and an outside sill portion at a lower level than said inside sill portion; of a ventilator comprising a casing structure adapted to be arranged within the window opening with a front part supported by the inside sill portion and a rear part overhanging said outside sill portion; said casing including a cover member hinged along one side so that it may be readily opened and access may be had to the rear interior thereof; and adjustable supporting and leveling means for supporting the rear of said ventilator and accessible for adjustment only from the interior of the casing when the cover is opened, and comprising nut devices fixed to the bottom wall of the casing and adjustable jack screws operable from the inside of the ventilator and threadedly engaging, respectively, the nut devices and extending downwardly through openings in the bottom wall and engaging at their lower ends the outside sill portion. 10

3. The combination with a window comprising 15 upright jambs, a window sash slidably mounted in the jambs and a window sill including an inside sill portion and an outside sill portion at a lower level than said inside sill portion; of a ventilator comprising a casing structure adapted to be arranged within the window opening with a front part supported by said inside sill portion and a rear part overhanging said outside sill portion; said casing including a cover part hinged along its rear side to the rear part of the ventilator so that it may be moved upwardly and rearwardly to open position; the forward part of said cover being provided with a sealing means adapted to be engaged by the under surface of the window sash when the cover is closed and the sash lowered; and adjustable supporting and leveling means arranged within the rear part of the 20 ventilator and accessible only from the interior thereof when the window sash is raised and the cover opened and including an adjustable part extending downwardly through an opening in the bottom wall of the casing and engaging the 25 outside sill portion for supporting the rear part of the ventilator from the outside sill portion. 30

4. The combination with a window comprising 35 upright jambs, a window sash slidably mounted in the jambs and a window sill including an inside sill portion and an outside sill portion at a lower level than said inside sill portion; of a ventilator comprising a casing structure adapted to be arranged within the window opening with a front part supported by said inside sill portion and a rear part overhanging said outside sill portion; said casing including a cover member hinged along its rear side to the rear part of the ventilator so that it may be moved upwardly and rearwardly to open position; a sealing strip 40 carried by the forward part of said cover and adapted to be engaged by the under surface of said window sash when the latter is lowered; an upright flange carried by the cover at the forward side of the sealing strip and adapted to lie substantially parallel to and adjacent the forward face of the window sash; and adjustable supporting and leveling means arranged within the rear part of the ventilator and accessible only from the interior thereof when the cover is opened 45 and operable to support the rear part of the ventilator from the outside part of the window sill and to align said flange with the forward face of the window sash. 50

5. The combination with a window comprising 55

upright jambs, a window sash slidably mounted in the jambs and a window sill including an inside sill portion and an outside sill portion at a lower level than said inside sill portion; of a 5 ventilator comprising a casing structure adapted to be arranged within the window opening with a front part supported by the inside sill portion and a rear part overhanging said outside sill portion; said casing including a cover member hinged 10 along one side so that it may be readily opened and access may be had to the rear interior thereof; a nut device secured to the bottom of the casing in the interior thereof and comprising a

horizontal part fixed to the bottom wall, a second horizontal part arranged above said first horizontal part in spaced relation thereto, and a vertical part connecting said horizontal parts, both of said horizontal parts and the bottom of the casing having aligned openings with the openings in the horizontal parts being screw-threaded; and a jack screw threadedly engaging the openings in the horizontal members and extending downwardly and engaging at its lower end the 10 outside sill portion. 5
